PEDAL STRUCTURE FOR ELECTRONIC PIANO
Clifford W. Andersen, De Kalb, Ill., assignor to The Rudolph Wurlitzer Company, Chicago, Ill., a corporation of Ohio

Filed Nov. 27, 1956, Ser. No. 624,583
16 Claims. (Cl. 84—1.13)

This invention is concerned generally with the electronic musical art, particularly with an electronic piano, and more specifically with a pedal structure forming a part thereof.

The pianoforte, commonly known as the piano, as is generally known, is a very popular musical instrument, and is known substantially throughout the world. One disadvantage of the conventional piano is that it is heavy and bulky. It also is rather expensive. The rather substantial size and weight of a conventional piano make transportation thereof difficult, and completely preclude carrying the instrument about from one place to another. Furthermore, the size and weight of a piano generally limit its use to the first floor of a building, and usually to the parlor of a residence. This is undesirable both from the standpoint of the student, and from the standpoint of others in the home.

Accordingly, it has been proposed that the size and weight, and also the cost, of a piano be reduced by the provision of an electronic piano. It is known that a tuned reed having an electrical potential applied to the reed and vibrated near a conductor will form with that member a variable capacitance giving rise to an electrical oscillation which can be translated into a musical tone. This invention is concerned with such a piano.

It will be appreciated that a piano must have a foot pedal for playing loud or "forte." However, the provision of such a pedal in a portable instrument causes many difficulties, both in the configuration of the pedal itself, and in its attachment to the piano case. Any appendage, such as a "loud" pedal inhibits portability of the instrument.

This invention is concerned with the provision of an improved pedal structure for a portable electronic piano.

It is a further object of this invention to provide, in a portable electronic piano, a detachable pedal structure which is easily transported, and which is readily attached to the piano for use.

A more specific object of this invention is to provide a detachable pedal for a portable piano which is readily detached from or attached to a piano, and which has easily operable means for adjusting the pedal relative to the remainder of the piano mechanism.

Other and further objects and advantages of the present invention will be apparent from the following description when taken in connection with the accompanying drawings wherein:

FIG. 1 is a perspective view of an electronic piano, constructed in accordance with the principles of this invention;

FIG. 2 is a cross-sectional view through the piano taken substantially along the line 2—2 in FIG. 3;

FIG. 3 is a fragmentary, horizontal sectional view taken substantially along the line 3—3 in FIG. 2;

FIG. 4 is a fragmentary end view of the piano showing the mechanism for attaching the pedal structure to the piano, part of the attaching case being broken away to show the inside parts;

FIG. 5 is a vertical sectional view taken substantially along the line 5—5 in FIG. 4;

FIG. 6 is a horizontal sectional view taken substantially along the line 6—6 in FIG. 4;

2

FIG. 7 is a horizontal sectional view substantially along the line 7—7 in FIG. 4;

FIG. 8 is a vertical sectional view through the foot pedal as taken substantially along the line 8—8 in FIG. 1;

FIG. 9 is a fragmentary sectional view corresponding to a part of FIG. 2 and showing a different piano action, and a different mechanism for attaching the pedal structure to the piano;

FIG. 10 is a horizontal sectional view taken substantially along the line 10—10 in FIG. 9;

FIG. 11 is a vertical sectional view through the foot pedal, similar to FIG. 8, and showing a modification thereof;

FIG. 12 is another vertical section through a foot pedal, this being a preferred form, as taken substantially along the line 12—12 in FIG. 13;

FIG. 13 is a vertical sectional view taken substantially along the line 13—13 in FIG. 12;

FIG. 14 is a perspective view of the cover or housing for the pedal structure of FIGS. 12 and 13;

FIG. 15 is a perspective view of the supporting bracket forming a part of the foot pedal structure of FIGS. 12 and 13; and

FIG. 16 is an exploded perspective view of the parts for attaching the foot pedal to the supporting bracket.

Referring now in greater particularity to the drawings, and first to FIGS. 1—3, there will be seen an electronic piano 30 constructed in accordance with the principles of my invention. The piano includes a case generally designated by the numeral 32. At the front of the piano there is provided a keyboard 34 comprising a plurality of keys 36 corresponding to the keys of a conventional piano, some of these keys being white, and some being black. The case also includes a fall board assembly 38 and a wire music rack 40 pivotally mounted thereon and movable from the upright position shown in FIGS. 1 and 2 to a folded down position (not shown).

The piano case is mounted on four legs 42 detachably connected to the piano by means hereinafter to be set forth. A foot pedal 44 for releasing the dampers is detachably connected to the piano by means of a flexible cable 46 of the type known as a Bowden cable. The piano is provided with an electronic amplifier shown in outline at 47 in FIG. 3 mounted within the case at the left end thereof and on the bottom of the case near the rear corner. The amplifier is connected to a loudspeaker 48 which opens through suitable louvers (not shown) in the back of the case. Controls and jacks 50 for the amplifier are provided at the side of the case.

A wooden bed 52 is mounted on the bottom of the case on the inside thereof, and a balance rail 54 extends across this bed. The keys 36 of the keyboard 34 are pivotally mounted on the balance rail by means of the usual balance key pins 56, and felt pads or washers 58 surrounding the pins. The top surface of the balance rail is inclined as will be appreciated so as to support the keys in the inclined position shown in the drawings with the inner ends of the keys 36 resting on a felt pad 60 at the inner edge of the bed. At the outer or front end of the bed 52 there is provided a front rail 62 carrying a plurality of pairs of front key pins 64. A felt pad 66 is provided on the front rail at the outer edge thereof immediately beneath the outer ends of the keys 36. This pad 66 forms a positive limit for downward movement of the outer ends of the keys and thereby prevents the keys from pivoting about the felt washers usually provided about the outermost of the front key pins. Such undesirable pivoting would result in rising of the keys from the balance rail, and it will be appreciated that this is extremely undesirable.

A pair of wood blocks 68 is mounted on the oppo-

site ends of the piano case 32 on the inside thereof. These blocks are screwed and glued in place. A reed bar assembly 70 is mounted on these blocks. The reed bar assembly is disclosed in detail in my Patent 2,881,651 dated April 14, 1959, and includes a reed bar 72 of massive construction, preferably cast of grey iron. The reed bar is generally rectangular in configuration and supports a plurality of vibratile reeds 74 and associated pickup means 76 capacitively related to the reeds. The reeds are electrically connected to the bar, while the pickup means 76 are insulated therefrom by an insulating sheet or bar 78. An aluminum shield 80 is placed over the pickup means and the outer ends of the reeds to eliminate hum in the output of the piano, the shield being lined with felt as at 81 and having a rubber pad 82 placed between the shield and the front edge of the reed bar to prevent vibration of the aluminum shield.

The reed bar is mounted by means of wood screws 84 passed through suitable apertures in the bar. These wood screws also are passed through rubber washers 86 on top of fiber washers 88 and are screwed into the wood blocks 68, the wood blocks being pre-drilled for this purpose. At the bass end of the bar there are two wood screws 84, while at the treble end there is only one wood screw, since the treble end is somewhat narrower than the bass end of the bar.

A main rail 90 extends across the piano, being supported at its opposite ends by suitable blocks 91 which are screwed and glued to the inside of the piano case. A plurality of whip flanges 92 is spaced along the bottom rear corner of the main rail, and a whip 94 is pivotally carried by each of the whip flanges 92. Each whip is provided beneath its forward end with a felt pad 96, and a capstan screw 98 on the inner end of the corresponding key 36 engages beneath each felt pad 96. The capstan screws preferably are provided with square or other noncircular shank sections for receiving a wrench for adjusting the capstan screws up and down beneath the ends of the whips.

A jack or fly 100 is pivotally mounted on each whip adjacent the felt pad 96 and projecting upwardly therefrom. Each jack or fly 100 engages beneath a butt 102 of a corresponding hammer 104 having a felt pad or striker 106 on the end thereof. A plurality of butt flanges 108 is spaced along the main rail 90, and these butt flanges pivotally support the butts 102. Each butt is provided with a recessed portion 110, with a jack engaging screw 112 for adjustably determining the time at which the jack or fly ceases to lift the butt and hammer, and with an adjusting screw 113 for determining the rest position of the butt. A butt spring 114 holds each hammer in lowered position as will be appreciated.

The hammers 104 are positioned to engage beneath the reeds 74 as readily will be understood. A damper lever 116 is positioned above each of the reeds except the top few at the treble end, and a damper 118 in the form of a felt pad is placed on each damper lever and engages a corresponding reed to damp the same. Each damper lever 116 is pivotally mounted on a damper lever flange 120, there being a plurality of such flanges positioned along the top rear edge of the main rail 90. A spring 122 associated with each damper lever holds the dampers in damping position. A damper lever wire 124 has its tail pivotally hooked through the inner end of each whip as at 126, and has its corresponding upper end projecting through the rear or inner end of the corresponding damping lever 116. A damper regulator button 127 is threaded on the upper end of each damper wire for adjusting the damper action.

It will be appreciated that each time a key is depressed the corresponding capstan screw 98 pivots the associated whip in counter clockwise direction as viewed in FIG. 2. This causes the jack or fly 100 to push up beneath the butt 102, thereby to pivot the corresponding hammer 104 into percussive engagement with the corresponding reed 74 to vibrate the same. The last part of this motion

is due to the inertia of the butt and hammer inasmuch as the screw 112 pushes the jack or fly 100 from jacking position at a predetermined location. Pivoting of the whip also pulls down on the corresponding damper wire 124 and accordingly pivots the corresponding damper lever 116 to retract the damper 118 from the reed that is to be engaged by the hammer, thereby freeing this reed for vibration and tone generation. Some of the treble reeds have such extremely short vibration times that no dampers are necessary. Accordingly, as has been noted heretofore, the dampers are omitted for some of the treble reeds. However, dummy damper levers are provided which are terminated short of the reed bar 72 so that the feel of the keys will be uniform. A block 128 is mounted at each end 10 of the main rail 90 and pivotally supports a damper release rod 130 for eccentric rotation about mounting pins or rods 132. The Bowden wire 46 connected to the foot pedal 44 is connected by means hereinafter to be described to the pin 132 at the treble end of the piano for eccentrically rotating the rod 130 to lift this rod against a pad 134 on the underside of each of the damper levers simultaneously to retract all of the dampers. Further details on the foregoing damper mechanism are fully set forth in my Patent 2,888,851 issued June 2, 1959. The 15 main rail also is provided with a T-shaped aluminum rail stiffener 136 which is suitably screwed to the back of the main rail and extends therealong.

The case 32 includes ends 138 and a back 140 made of a single sheet of plywood molded generally in accordance with conventional practices. The plywood sheet comprising the ends and back rests on top of a bottom 142, also formed of plywood, and of the same outline as the back and ends. The back and ends are glued to the bottom 142, and preferably also are secured with small 20 nails or screws. The forward corners of the ends 138 are cut down or relieved as is indicated at 144 to provide end clearance for the key-board, thus avoiding any feeling in the part of the pianist of being confined or "boxed in."

25 The blocks 68 are secured to the opposite end-pieces 138, as previously has been indicated, and also rest on the bottom 142, preferably being glued and screwed both to the ends and to the bottom. Besides providing a mount for the reed bar assembly, these blocks also help to reinforce the joint of the case as will be appreciated. 30 Similarly, the blocks 91 are glued and screwed to the end of the case. The upper corners of the blocks 91 are relieved to accommodate the main rail 90, as will be appreciated. In addition to the foregoing, there are blocks 152 secured to the ends near the fronts thereof. These 35 blocks serve as filler blocks at the opposite ends of the keyboard, and also support the fall board assembly 38 at the corners thereof. A pair of cleats 154 is secured to the ends 138 adjacent the top edges thereof, and a similar cleat 156 coplanar with the cleats 154 is secured to the inner surface of the back. The cleats serve to support the top 158 with the top nesting within the ends 138 and back 140.

40 The back 140 is provided with horizontal slots (not shown) forming a louver for the loud-speaker 48, as will be appreciated, and on the outside of the back 140 there is secured a plurality of wooden cleats 159 which serve as a rest for the piano when it is carried in suitcase fashion, and it is desired to set the case down.

45 Details of one form of forte pedal mechanism 44 and the connection thereof to the piano are shown in FIGS. 4-8. Thus, there is provided a housing or case 160 of generally rectangular configuration and having a mounting surface or wall 162. The sheath of the Bowden cable 46 passes into the housing 160, preferably through a rubber grommet 164, and the inner end of the sheath is anchored against a block 166 by a clamp 168 held by screws 170 threaded into the block. A stud having a knurled knob 172 extends through a horizontal slot 174 50 in the side of the housing 160, and adjustably clamps the

block 166 in place, adjustably to locate the end of the sheats of the Bowden cable 46.

A pair of threaded studs 176 passes completely through the housing 160 and is held against complete retraction therefrom by self-locking nuts 178 threaded on the studs. The studs 176 are provided with knurled heads or knobs 180 to allow facile finger operation thereof, and the inner ends of the studs are detachably threaded into T-nuts 182 mounted on the inside of the end 138 of the piano case. The piano case has openings therethrough communicating with the T-nuts, as will be understood. The housing 160 thus is detachably held on the end of the piano case.

The mounting wall 162 of the housing 160 is provided with a bushing 184 adapted to project into an opening 186 in the end of the piano case in alignment with the pivot pins 132. The bushing 184 is secured in the wall 162 by a press fit, or other suitable means. A sleeve 188 extends through the bushing and has a slotted inner end including a pair of diametrically opposed, longitudinally extending slots 190. The inner end of the sleeve 188 receives the adjacent pivot pin 132 with a cross pin 192 of the pivot pin received at its opposite ends in the slots 190 for rotating the pivot pin with the sleeve. A split washer 194 is received in an annular groove in the sleeve to prevent retraction of the sleeve from the bushing. The outer end of the sleeve 188, which may be solid if so desired, extends through the end of a lever 196, and is peened over as at 197, although the lever can be affixed in a different manner if so desired. It will be understood that the outer end of the sleeve is provided with a non-circular section received in an aperture of corresponding shape in the lever 196 to insure turning of the sleeve with the lever. The opposite end of the lever 196 is provided with a right-angularly disposed flange 198 to which a locking plate 200 is secured by means such as a nut and bolt 202. The end of the operating member of the Bowden cable projects through this locking plate and has a ball 204 clamped on the end thereof in the usual fashion to insure pivoting of the lever in a counter-clockwise direction as viewed in FIG. 4. A spring 206 is coiled about the end of the sleeve 188 adjacent the lever 196, and has one end bearing on the lever at 208, the opposite end engaging at 210 behind a lug or stop 212 struck out of the rear wall 162 of the housing 160. An additional spring 214 is stretched between the lever and an anchor on rear wall 162, and the two springs 206 and 214 coact to hold the lever in a clockwise pivoted rest position as shown in FIG. 4. It will be appreciated that the provision of the two springs imparts a different type of resistance to movement of the lever than would a single spring, thereby adding a piano-like feel to the forte pedal beneath the pianist's foot. One embodiment of the pedal structure 44 is shown in FIG. 8. This structure comprises a base plate 216 having a rubber pad 218 on the underside thereof, the rubber pad having a corrugated surface for anchoring the pedal structure against skidding. A heel plate 220 is hingedly connected to the base plate 218 at 222, the latter preferably being a detachable hinge, and a rubber pad 224 on the bottom of the heel plate 220 forms a continuation of the pad 218. The heel plate is provided with a rubber pad cover 226, and a continuation of the cover is applied to the top of the base plate 218 as at 228. It will be understood that all of the pads preferably are adhesively attached to the respective plates, and that the outer surfaces of all of the pads are corrugated for skid resistance.

An inverted, generally cup-shaped housing 230 is secured on top of the plate 218 by suitable means such as screws 232 passing through the plate and threaded into the housing. The housing preferably is cast of relatively soft metal such as aluminum, or may be molded of plastic, and the screws 232 may comprise wood screws or sheet-metal screws threaded into drilled openings in the

housing 230. A bracket 234 is secured against the rear wall of the housing by means such as screws 236, and a lever 238 is pivotally mounted on bracket 234, being urged upwardly by a helical spring 240. The lever 238 extends outwardly of the housing through a vertical slot 242 therein, and is provided with a toe portion 244 engagable by the pianist's toe. Resilient stops 246, such as of foam rubber, are provided at the top and bottom of the slot 242 to insure noiseless operation.

An inverted U-shaped bracket 248 is secured to the underside of the top of the housing by means such as screws 250. The bracket serves as an anchor for the spring 240, and it further cooperates with a clamp 252 to form an anchor for the end of the sheath of the Bowden cable 46. The lever 238 is apertured at 254 in alignment with the Bowden cable, and the operating member or wire thereof extends through the hole 254, and has a ball 256 clamped thereon whereby the operating member of the Bowden cable is secured by an anchor plate 258 secured by means such as a screw 260 to the underside of the lever 238, the lever preferably being recessed as is indicated at 262. In the operation of the forte pedal 44, the pianist's heel rests on the pad 226 of the heel plate 220 to anchor the pedal structure. When the pianist's toe depresses the toe portion 244 the operating member of the Bowden cable is pulled down. This causes the operating member to pivot the lever 196 in a counter-clockwise direction as viewed in FIG. 4, and this in turn effects eccentric pivoting of the damper release rod 130. The damper release accordingly rises up beneath all of the damper levers, and thereby simultaneously retracts all of the dampers for undamped or forte playing. As will be appreciated, loosening of the stud having the knurled head 172 allows axial adjustment of the block 160, whereby adjustably to position the anchored position of the Bowden cable. This allows initial adjustment so that there will be no lost motion in the pedal mechanism, and so that the pedal mechanism will not, in rest position, tend to hold the dampers partially retracted.

A modified form of the invention is shown in cooperation with a slightly changed form of piano action in FIGS. 9 and 10. Most of the parts of the piano action are similar to the parts previously described with regard to FIGS. 2 and 3, and similar parts are identified by the use of similar numerals, with the addition of the suffix *a*. Most of the parts will be self-evident from the use of similar numerals, and significant differences are set forth hereinafter. One point of difference is that the fly 100a is pivoted to the hammer or butt as at 262, and is raised directly by the capstan screw 98a on the key 36a. A butt spoon 264 depending from the butt 102a holds the fly 100a in the position shown, with the parts at rest. However, when the key is pivoted and the fly and butt are raised, a butt regulating screw 266 threaded through an up-standing part 268 on the butt engages a felt pad on the upper end of the fly to pivot the fly, whereby the capstan screw 98a is positioned beneath a recess 269 in the fly. The lifting action of the fly thus comes to an end, and the butt continues to rise under the influence of its own inertia until the pad 106a on the hammer head 104a engages the corresponding reed 74a.

It will be observed in this form of the invention that the damper release wire 124a of each of the individual actions pushes up beneath the damper release lever 116a, rather than pulling on the tail of it, as in the previous embodiment.

Intermediate the ends of the damper release rod 130a, there is a lever 270 welded across the top of the damper release rod and extending horizontally toward the rear of the cabinet. A damper release connecting rod 272 is pivotally connected to the lever at 273, and extends vertically downwardly into an aperture 274 in the bottom 142a of the piano case 32a, the connecting rod 272 being terminated substantially at the outer face of the bottom, and having its tip threaded as at 276. The con-

necting rod extends through a member 278 supported at its opposite ends by blocks 280 shortly above the bottom 142a. A coil spring 282 encircles the connecting rod 272 and is compressed between a spring seat 284 fixed thereon, and a spring seat on the member 278. A nut 286 is threaded on the upper end of the tip 276.

The bottom 142a is provided with a T-nut 288, which receives a thumb screw 290 passing through an angle bracket 292. The bracket has a long arm 294 in vertical position, and a generally U-shaped housing or cover 296, open at both ends, is secured to this arm. The arm is provided near its lower end with a vertical slot 298, and a thumb screw 300 extends through this slot and is threaded into an anchor block 302. A clamp 304 secured on the anchor block by screws 306 anchors the upper end of the sheath of the Bowden cable 46a. The position of the anchor block 302 is adjustable, as will be apparent, in order to determine the position of the end of the sheath. A cylinder 308 is swivelly connected to the upper end of the inner wire or operating member of the Bowden cable, and is provided with internal threads whereby to receive the threaded tip 276 of the connecting rod 272. As will be appreciated, the cylinder 308 abuts the nut 286 to limit the position of the cylinder on the connecting rod.

It will be appreciated that the cylinder 308 is readily connected to, or disconnected from, the connecting rod 272 by simply rotating the cylinder. Similarly, the bracket 292 is readily associated with, or separated from, the case 32a by rotating the thumb screw 290 in the appropriate direction. Preferably, a washer or section 310 of friction material is incorporated between the bracket 292 and the bottom 142a of the case to preclude twisting of the bracket when in installed position. This friction material preferably is cemented or otherwise permanently secured to the bracket.

In both of the foregoing forms of the invention, adjustment for the upper end of the Bowden cable is provided in order to insure against lost motion, or partial raising of the dampers at all times. It is to be understood that this is the preferred arrangement, but it is contemplated that adjustment could be made at the bottom end of the cable as is shown in FIG. 11. In this instance, the parts of the foot pedal structure 44b are similar to those shown and described with regard to FIG. 8. Similar numerals are utilized to identify similar parts, with the addition of the suffix *b*. The difference is that there is provided a U-shaped bracket 312 on the underside of the lever 238b, the bracket being secured by means such as screws 314 threaded throughoutwardly extending feet on the bracket and into the lever. An adjusting screw 316 is threaded through the bight of the bracket 312, and secures a hook-shaped retaining member 318 between a pair of nuts 320 thereon. The hook-shaped retaining member forms a swivel connection with the ball 256b on the end of the inner or operating member of the Bowden cable 46b. An aperture is provided in the base plate 216 and rubber cover 218 in alignment with the adjusting screw 316, as will be understood, for screwdriver adjustment of the lower end of the operating member of the Bowden cable.

A preferred form of pedal structure is illustrated in FIGS. 12-16. Many of the parts are similar to, or correspond to parts previously described, and accordingly similar numerals are utilized with the addition of the suffix *c*. Thus, the base plate 216c and heel plate 220c remain the same, as do the cooperating rubber covers. A plurality of angle brackets 322 is spot welded to the top of the base plate 216c, and the housing or cover 230c, which in this instance is stamped of sheet metal, is held on top of the base plate by means of screws 324 passing through the housing and threaded into the upstanding flanges of the brackets 322. The screws 324 conveniently are sheet metal screws, and as will be apparent, the cover is readily removed from the base.

5 A rather large, inverted channel or U-shaped bracket 326 is secured on the base plate 216c within the cover 230c. The bracket 326 includes a pair of sidewalls 328 interconnected by a web 330, and having outwardly directed flanges 332 on the lower edges. Near the upper rear corners of the sidewalls 328, there is provided a pair of aligned, square apertures 334 opening to the rear edges of the walls 328 by means of restricted slots 336. The flanges 332 are spot welded to the base plate 216c to mount the bracket along the longitudinal center line of the foot pedal structure, and relatively toward the back of the cover 230c.

10 The lever 238c is supported by the bracket 326. To this end, the lever is provided at its rear or inner end with a cross-pin 338 which is press-fitted in the lever. The cross-pin is shifted through the slots 336 into the apertures 334, and plastic bearing grommets 340 are inserted into the apertures 334, and about the pin 338 to form a bearing therefore. The plastic bearing 340 is of a type known in the art, having a round head 342, with a pair of resilient fingers forming a split shank 344 extending axially therefrom. A cylindrical bore 346 extends axially through the grommet. The shanks are square in cross-section, as will be appreciated, for 15 operation with the square apertures 334. The plastic grommets are of a type well-known in the art, and for example may be "Shakeproof" grommets.

20 A bracket 348 is secured to the base plate 216c relatively toward the front of the cover, and along the center line 30 of the pedal structure. More particularly, the bracket comprises a central strip or web 350 which is spot welded to the base plate. At the front edge of the cover the bracket 348 extends upwardly to form a flange 352, and a reversely directed flange 354 is provided at the top of the flange 352. A felt or other resilient pad 246c is mounted on the flange 354, and forms the lower limit stop. At the rear of the strip or web 350, there is a short vertical flange 356, having a wider horizontal flange 358 extending rearwardly therefrom and at the top thereof. The flange 358 is apertured, and a plastic spring-retaining button 360 is mounted therein. The button is similar in nature to the grommets 340, but does not need a central bore. A compression spring 362 is centered by the spring bearing button 360, and by a boss 364 on the underside of the lever 238c, and urges the lever up against 25 the upper limit stop 246c.

30 A metal tab or strip 366 is welded to the web 330 of the bracket 326 on the underside thereof, and extends to the front of the cover 230c at the top of the slot 242c therein. The felt or other resilient material 246c at the 35 top of this slot is cemented or otherwise suitably secured to the strip or tab 366. Substantially at the same location and on top of the web 330, there is welded an angle bracket 368. A clamp 370 is held on this angle bracket by means such as screws 372, and serves to anchor the lower end of the sheath of the Bowden cable 46c, as will be apparent. The strip or tab 366 is provided with an aperture 374 to provide clearance for the inner or operating member of the Bowden cable, and the end of this operating member is anchored to the lever 238c in the manner heretofore described, including the ball 256c, and the anchor plate 258c.

40 The form of the foot pedal structure shown in FIGS. 12-16 is preferred because all of the parts can be assembled with the cover off, it being understood that the cover is slipped part way up the Bowden cable before the cable is assembled with the parts of the foot pedal structure. Accordingly, assembly is greatly simplified, and servicing 45 readily can be done upon removing of the cover.

45 The foot pedal structure shown in FIGS. 12-16 can be used in cooperation with the attaching mechanism of FIGS. 4-7, or with that of FIGS. 9 and 10.

50 In each instance, a foot pedal structure is provided which is detachable from the portable piano, and hence 55 does not detract from the portability of the piano, and in

fact, is readily portable therewith. Provision is made for adjusting the attachment to insure that the dampers will not be held retracted at all times, and further to insure against lost motion, and to insure against failure of the foot pedal completely to retract the dampers.

The various examples of the invention as herein shown and described are for illustrative purposes only. It is to be understood that various changes in structure such as might occur to those skilled in the art form a part of the invention insofar as they fall within the spirit and scope of the appended claims.

The invention is claimed as follows:

1. In an electronic piano comprising a case, a keyboard on said case, electronic tone generating means mounted within said case and selectively controlled by the keys of said keyboard, means for controlling the decay characteristics of said tone generating means, an amplifier for amplifying the oscillations of said tone generating means, a loud-speaker for converting the amplified electrical oscillations into audible musical tones, the combination comprising a foot pedal disposed remotely and movably relative to said case, means including a flexible push-pull control of the type having a flexible sheath and a flexible inner control member and quick-release fastening means connecting the tone generation decay characteristic control means and said foot pedal, and means associated with said foot pedal for varying the connecting position of said foot pedal to said inner control member.

2. A pedal structure for pianos and the like comprising a base plate, a housing on said base plate, said housing having an opening therein, a pedal pivotally mounted in said housing and extending out of said housing through said opening, a push-pull control of the type having a flexible outer sheath and a flexible inner operating member, means anchoring said flexible outer sheath relative to said housing and means connecting the flexible operating member to said pedal, and a heel plate extending from said base plate substantially in the same direction as said pedal, whereby a player may rest his heel on said heel plate to anchor said pedal structure against movement when said pedal is depressed by the player's foot.

3. A pedal structure as set forth in claim 2 and further including a bracket on said base plate, said pedal being pivotally mounted on said bracket.

4. A pedal structure as set forth in claim 2 wherein the pedal is pivotally supported from said housing.

5. A pedal structure as set forth in claim 2 wherein the opening in the housing comprises a slot, and resilient stop means at opposite ends of said housing engageable with said pedal to limit upward and downward pivotal movement.

6. A pedal structure as set forth in claim 2 wherein said heel plate is pivotally and detachably secured to said base plate by a split hinge.

7. In a portable piano comprising a case, a keyboard on said case, tone generating means mounted within said case and selectively controlled by the keys of said keyboard, means in said case and operatively connected to the tone generating means for controlling the decay characteristics of said tone generating means, the combination comprising a foot pedal structure disposed remotely and movably relative to said case including a housing and a pedal, means including a push-pull control of the type having a flexible sheath and a flexible inner control member connecting the tone generation decay characteristic control means and said foot pedal, means providing a quick-detachable connection between said push-pull control and said case and tone generation decay characteristic control means, and means associated with said push-pull control for effecting adjustment of the position of said foot pedal relative to said tone generation decay characteristic control means.

8. The combination set forth in claim 7 and further including a plurality of anchors at opposite ends of said

push-pull control, said anchors respectively anchoring said sheath relative to said piano case and relative to said foot pedal housing, and anchoring said inner control member relative to said foot pedal and relative to said tone generation decay characteristic control means, wherein the means for effecting initial adjustment comprises stud-and-slot means for adjusting the position of one of said anchors.

9. In a portable piano comprising a case, a keyboard on said case, tone generating means mounted within said case and selectively controlled by the keys of said keyboard, means for controlling the decay characteristics of said tone generating means, a connector operatively connected to said tone generation decay characteristic control means for operating the same, said connector being accessible through a wall of said case and said wall being suitably apertured therefor, the combination comprising a foot pedal structure remote from said case and movable relative thereto including a support and a movably mounted pedal, a push-pull control of the type having a flexible sheath and a flexible inner control member connected at one end respectively to said support and to said foot pedal and at the other end respectively to a fitting detachably connectable to said piano case, and to a second connector detachably connectable to said first mentioned connector.

10. The combination as set forth in claim 9 wherein the fitting comprises an angle member securable to said case, and an anchor member secured to the sheath of said push-pull control and adjustably carried by said angle member.

11. In a portable piano comprising a case, a keyboard on said case, tone generating means mounted in said case and selectively controlled by the keys of said keyboard, means for controlling the decay characteristics of said tone generating means, a rotary member operatively connected to said decay characteristic control means and accessible through a wall of said case, said case having an aperture therein adjacent said control means, the combination comprising a rotary connector adapted to extend through said aperture and detachably connectible to said rotary member, a lever on said rotary connector for rotating the same, a fitting associated with said rotary connector and detachably connectable to said case, a foot pedal structure disposed remotely and movably relative to said case and comprising a support and a foot pedal, and a push-pull control of the type having a flexible sheath and a flexible inner control member, said flexible inner control member being connected at its opposite ends to said foot pedal and to said lever, and said flexible sheath being connected at its opposite ends to said support and to said fittings.

12. The combination as set forth in claim 11 and further including an anchor member adjustably mounted on said fitting and secured to said sheath.

13. A pedal structure for pianos and the like comprising a base plate, an inverted, substantially U-shaped bracket secured to said base plate, a pedal pivotally mounted on said bracket and extending generally in the same direction as said base plate, a push-pull control of the type having a flexible sheath and a flexible inner control member, means connecting said flexible inner control member to said pedal, means securing said flexible sheath to said bracket, and a housing secured to said base plate and enclosing said bracket and securing means and a part of said pedal, said housing having an opening through which a toe portion of said pedal extends.

14. A pedal structure as set forth in claim 13 and further including a member secured to said base plate and having raised end portions, one of said raised end portions being adjacent the opening in said housing and forming a stop for said pedal, and the other of said raised portions forming a spring abutment, and further including a spring compressed between the pedal and said

spring abutment and urging said pedal in a given direction.

15. In a portable piano comprising a case, a keyboard on said case, tone generating means mounted within said case and selectively controlled by the keys of said keyboard, means in said case operatively connected to said tone generating means for controlling the decay characteristics of said tone generating means, the combination comprising a foot pedal structure disposed remotely and movably relative to said case and comprising a base plate, a housing on said base plate, said housing having an opening therein, a peripherally unobstructed pedal pivotally mounted in said housing and extending out of said housing through said opening, a push-pull control of the type having flexible outer sheath and a flexible inner operating member, means anchoring said outer sheath relative to said housing and means connecting the operating member to said pedal, a substantially flat heel plate extending from said base plate substantially in the same direction as said pedal in spaced relation therebelow, whereby a player may rest his heel on said heel plate to anchor said pedal structure against movement when said pedal is depressed by the player's foot, quick release means connecting the push-pull control to said decay characteristic controlling means and means associated with said push-pull control for effecting adjustment of the position of said foot pedal relative to said tone generation decay characteristics control means.

16. In a portable piano comprising a case, a keyboard on said case, tone generating means mounted within said case and selectively controlled by the keys of said keyboard, means in said case operatively connected to said

tone generating means for controlling the decay characteristics of said tone generating means, the combination comprising a substantially flat pedal base plate disposed remotely and movably relative to said case, an inverted, substantially U-shaped bracket secured to said pedal base plate, a pedal pivotally mounted on said bracket and extending generally in the same direction as said base plate, a push pull control of the type having a flexible sheath and a flexible inner control member, means connecting said flexible inner control member to said pedal and to said tone generation decay characteristic control means, means securing said flexible sheath to said bracket and to said case, the connecting means to said control means and to said case being quickly detachable connecting means, and a housing secured to said base plate and enclosing said bracket and securing means and a part of said pedal, said housing having an opening through which a toe portion of said pedal extends.
